UNITED STATES PATENT OFFICE.

NELSON R. HAAS, OF DAYTON, OHIO, ASSIGNOR TO THE DAYTON ENGINEERING LABORATORIES COMPANY, A CORPORATION OF OHIO.

ARMATURE FOR DYNAMO-ELECTRIC MACHINES.

1,406,184.

Specification of Letters Patent. Patented Feb. 14, 1922.

Application filed July 14, 1919. Serial No. 310,789.

To all whom it may concern:

Be it known that I, NELSON R. HAAS, a citizen of the United States of America, residing at Dayton, county of Montgomery, State of Ohio, have invented certain new and useful Improvements in Armatures for Dynamo-Electric Machines, of which the following is a full, clear, and exact description.

10 This invention relates to the construction of armatures for dynamo-electric-machines for internal-combustion engines, and especially to the type of machine used in the electrical system of an automobile.

15 This invention is adapted especially for use in the construction of starting motors for automobile engines, or for use in the construction of dynamo-electric-machines which may be used either as starting motors or as generators, such machines having what is commonly known as double-wound armatures.

20 The chief object of the present invention is to construct an armature having one or more sets of windings which will occupy the least possible space. While carrying out this object it is a further aim of the invention to increase the efficiency of certain magnetic circuits included in the dynamo-electric-machine. One manner of carrying out this further aim of the invention is to construct the armature core in such a manner as to decrease the reluctance of the core teeth.

25 Other and further objects and advantages of the present invention will be apparent from the following description, references being had to the accompanying drawings, wherein a preferred embodiment of the present invention is clearly shown.

In the drawings:

Fig. 1 is a side elevational view of a double-wound armature constructed in accordance with the present invention;

45 Fig. 2 is a sectional view taken on line 2—2 of Fig. 1;

50 Fig. 3 is an end view of the armature shown in Fig. 1, as viewed from the right of the drawing, said view being partly in section, the section being taken on the line 3—3 of Fig. 1;

55 Fig. 4 is a fragmentary end view of the armature core showing certain of the windings in position, and showing the method of assembly of certain other windings;

Fig. 5 is an end view of one of the hairpin loops included in one of the sets of windings;

Fig. 6 is a plan view of the same;

Fig. 7 is a wiring diagram of the heavy 60 or flat bar windings of the electric machine and;

Fig. 8 is a wiring diagram of the relatively fine winding of the electric machine.

Referring to the drawings, 20 designates the armature shaft which carries an armature core 21 which is preferably laminated. This core is provided with a cylindrical periphery from which extend a plurality of equidistant grooves 22. Each of these 70 grooves 22 includes a relatively narrow portion 23 adjacent the core periphery and a relatively wider portion 24 further removed from the core periphery.

Before winding the armature, the grooves 75 are lined with insulation material 25 in any suitable, well-known manner. The windings of relatively fine wire, generally known as the generator windings 30, are then wound in position on the armature core in any desired fashion such as is illustrated diagrammatically in Fig. 8.

Referring to Fig. 8, 40 designates the generator commutator comprising a plurality of insulated segments. To one of these segments 41 is connected a generator winding 31 which extends, as shown in the diagram, through grooves 22^a and through a groove 22^b, and then across to commutator segments 42 which are spaced substantially 180° 90 from the segment 41. To commutator bar 43 is attached a second generator winding 32 which threads armature grooves 22^a and 22^b, and crosses over to commutator bar 44 which is substantially 180° from bar 43. This 95 style of winding is generally known as wave form and is frequently employed in constructing generator armature windings of the drum type. Other pairs of windings thread each of the armature grooves in the manner illustrated in Fig. 8, so that each of the grooves 22 is threaded by four sets of windings. In the embodiment of the invention shown, each winding comprises five turns so that each groove will contain 20 105 conductors as illustrated in Figs. 2 and 4. These generator conductors are located in the portions of the grooves which are farthest removed from the periphery of the armature core.

110

After all of the generator windings are applied in the manner indicated diagrammatically in Fig. 8, the flat bar windings of the motor armature circuit are then placed in position upon the armature core.

These flat bar windings comprise a plurality of independent hairpin-shaped conductors or loops 50, as shown in Fig. 6. Each of these loops 50 includes a branch 51 which is adapted to occupy the wider portion 24 of one of the grooves 22, and with a second branch 52 which is adapted to occupy a narrower portion 23 of one of the grooves 22.

It will be noted with reference to Fig. 3 that the cross-section of these bar conductors is substantially oblong or rectangular in shape. For purposes of comparison the major axis of symmetry or major axis of this bar section is designated by line 53 (see Fig. 5).

It will be noted that when the bars occupy the position shown in Figs. 2 and 4, a branch 51 occupies the wider portion 24 of one of the grooves 22 with its major axis 53 substantially parallel to the periphery of the core. At the same time the other branch 52 occupies the narrower portion 23 of another of the grooves 22 with its major axis 53 extending radially with respect to the core periphery or center of the core.

These hairpin loops 50 are assembled in position by placing the branches 52 of each of the loops in the wider portion 24 of all of the grooves, so that each of the grooves is occupied by a branch portion 51. This step in the process of assembling is illustrated in Fig. 4, wherein the position of the loops 50, is shown in full lines. The next step in the operation is to move the loops toward the armature core in order that the branches 52 of the loops may be forced into the narrower portion 23 of one of the grooves 22 and so that each branch 52 will be located outside of the branch portion 51 of another loop which occupies the same groove.

It will be understood that these conductors are covered with some insulating material such as insulating varnish or with an insulating sleeve in order that no electrical connection will be made between the branches of the hairpin loops which will occupy the same groove.

From the foregoing description it will be apparent that several advantages result from the construction of a dynamo armature in accordance with the present invention. In the first place the diameter of the armature core may be considerably reduced, by reason of the fact that the major axis of the two commutator conductors which occupy the same groove are not in radial alinement relatively to the core, but are at right angles to one another as described and illustrated.

A second advantage ensuing from the construction described resides in the fact that the portion of the armature grooves nearest the periphery can be made comparatively narrow, thereby tending to reduce the reluctance to the magnetic circuit offered by the armature core teeth, or that portion of the armature core included between adjacent grooves. This reduction of reluctance of armature teeth results in higher efficiency of the dynamo-electric-machine, and consequently it follows that the external dimensions of the armature will be less than in the case of an armature wherein the reluctance of the teeth has not been reduced in the manner disclosed.

A still further advantage resulting from the present invention is that the armature conductors are securely held in position in a very simple manner. The small generator conductors are held from flying upwardly due to centrifugal force, by means of the branch portions 51 of the bar conductors 50. After these bar conductors are assembled in position it will be seen that the portions 51 are locked in position by the wider groove portions 24. Since these branch portions cannot turn, there is no possible chance of them flying out through the narrow groove portion 23 which is considerably narrower than the width of the branch portions 53. Therefore the armature core itself may be said to cooperate with the branch portions 51 to lock the same and the generator windings 30 in position within the armature core. The outer branch portions 51 of the loops are held in position by reason of their connection at one end with the inner branches 51 and by reason of their connection with the motor commutator 60 which will be described hereinafter. The branch portions 52 are firmly maintained in position by the portions 51 by reason of the arch-shaped loop which connects these portions. This arch-shape is clearly shown in Fig. 5.

Referring now particularly to Fig. 7 it will be seen that the commutator 60 comprises a plurality of insulated segments 61 to which is attached a branch portion 51 and a branch portion 52 of each of two different hairpin conductors. For purpose of illustration, one of these conductors 50^a will be described: To one of the commutator segments 61, designated more particularly as 61^a, is attached one end of a branch 51^a of a conductor 50^a. The branch 51^a continues diagonally over to groove 22^a through said groove and then through a substantially V-shaped bend in which it merges into the branch portion 52^a. Branch portion 52^a extends through the wide portion of a groove 22^a and then diagonally across, making a quarter turn at the same time, and into engagement with a commutator bar 61^b 130.

which is substantially 180° from the bar 61^a. This form of windings is known as a wave form and commonly employed in applying windings to a drum-wound armature.

5 The ends of branches 51 and 52 are very securely attached to the commutator segments for the purpose of making a good electrical connection therewith and in order 10 that the commutator segments may assist in maintaining the branch portions 52 securely in position.

15 While the foregoing describes an armature for a dynamo-electric-machine having a field surrounding the armature, it is to be understood that the invention may be applied as well to the construction of armatures which are arranged to rotate around the exterior of a centrally disposed field.

20 While the form of mechanism herein shown and described constitutes a preferred form of embodiment of the invention, it is to be understood that other forms might be adopted, all coming within the scope of 25 the claims which follow.

What I claim is as follows:

1. In an armature of a dynamo-electric-machine, the combination with an armature core having a cylindrical periphery and 30 provided with spaced grooves extending from the periphery, each of the said grooves having a relatively narrow portion adjacent said periphery and a relatively wider portion farther removed from said periphery; 35 a plurality of bar conductors arranged to occupy the wider and narrower portions of said grooves and means for conducting current to and from said bar conductors.

2. In an armature of a dynamo-electric-40 machine, the combination with an armature core having a cylindrical periphery and provided with spaced grooves extending from the periphery, each of the said grooves having a relatively narrow portion adjacent 45 said periphery and a relatively wider portion farther removed from the said periphery; of flat bar conductors arranged to occupy the wider portions of said grooves with their major axes substantially parallel 50 to the core periphery, and flat bar conductors arranged to occupy the narrower portions of said grooves with their major axes extending radially of the core; and means for conducting current to and from 55 said bar conductors.

3. In an armature of a dynamo-electric-machine, the combination with an armature core having a cylindrical periphery and 60 provided with spaced grooves extending from the periphery, each of said grooves having a relatively wider portion farther removed from said periphery; of flat bar conductors constructed of a continuous 65 strip of conducting material each having a branch portion arranged to occupy the

wider portion of one of said grooves with its major axis substantially parallel with the core periphery, and having another portion arranged to occupy the narrower portion of another slot with its major axis 70 extending radially of the core; and means for conducting current to and from said bar conductors.

4. In an armature of a dynamo-electric-machine, the combination with an armature core having a cylindrical periphery and 75 provided with spaced grooves extending from the periphery; of flat bar conductors arranged to occupy portions of said grooves adjacent said periphery with their major axes extending radially of the core, and flat bar conductors arranged to occupy the portions of the grooves farther removed from the core periphery with their major axes substantially parallel with the 85 core periphery; and means for conducting current to and from said bar conductors.

5. In an armature of a dynamo-electric-machine, the combination with an armature core having a cylindrical periphery and 90 provided with spaced grooves extending from the periphery; of flat bar conductors constructed of a continuous strip of conducting material each having a branch portion arranged to occupy a portion of one 95 of said grooves adjacent the core periphery with its major axis extending radially of said periphery, and having another portion arranged to occupy a portion of another of said grooves farther removed from said 100 periphery with its major axis substantially parallel with the core periphery; and means for conducting current to and from said bar conductors.

6. In an armature of a dynamo-electric-105 machine, the combination with an armature core having a cylindrical periphery and provided with spaced grooves extending from the periphery each of said grooves having a relatively narrow portion adjacent 110 said periphery and a relatively wider portion farther removed from said periphery; a plurality of bar conductors arranged to occupy the wider and narrower portions of said grooves; a plurality of relatively 115 fine wire conductors arranged within said grooves in portions thereof farther removed from said core periphery and from said bar conductors; means of conducting current to and from said bar conductors; and means 120 for conducting current to and from the fine wire conductors.

7. In an armature of a dynamo-electric-machine, the combination with an armature core having a cylindrical periphery and 125 provided with spaced grooves extending from the periphery, each of said grooves having a relatively narrow portion adjacent 130 said periphery and a relatively wider portion farther removed from said periphery;

- of flat bar conductors arranged to occupy the wider portions of said grooves with their major axes substantially parallel to the core periphery, and flat bar conductors arranged to occupy the narrower portions of said grooves with their major axes extending radially of the core; a plurality of relatively fine wire conductors arranged within said grooves in portions thereof further removed from said core periphery and from said bar conductors; means for conducting current to and from said bar conductors; and means for conducting current to and from the fine wire conductors.
8. In an armature of a dynamo-electric machine, the combination with an armature core having a cylindrical periphery and provided with spaced grooves extending from the periphery, each of said grooves having a relatively narrow portion adjacent said periphery and a relatively wider portion farther removed from said periphery; of flat bar conductors constructed of a continuous strip of conducting material each having a branch portion arranged to occupy the wider portion of one of said grooves with its major axis substantially parallel with the core periphery, and having another branch portion arranged to occupy the narrower portion of another slot with its major axis extending radially of the core; a plurality of relatively fine wire conductors within said grooves in portions thereof farther removed from said core periphery and from said bar conductors; means of conducting current to and from said bar conductors; and means for conducting current to and from said fine wire conductors.
9. In an armature of a dynamo-electric machine, the combination with an armature core having a cylindrical periphery and provided with spaced grooves extending from the periphery; of flat bar conductors arranged to occupy portions of said grooves adjacent said periphery with their major axes extending radially of the core, and flat bar conductors arranged to occupy portions of the grooves farther removed from the core periphery with their major axes substantially parallel with the core periphery; a plurality of relatively fine wire conductors arranged within said grooves in portions thereof farther removed from said core periphery and from said bar conductors; means for conducting current to and from said bar conductors; and means for conducting current to and from the fine wire conductors.
10. In an armature of a dynamo-electric machine, the combination with an armature core having a cylindrical periphery and provided with spaced grooves extending from
- the periphery; of flat bar conductors constructed of a continuous strip of conducting material each having a branch portion arranged to occupy a portion of one of said grooves adjacent the core periphery with its major axis extending radially of said periphery, and having another branch portion arranged to occupy a portion of another of said grooves farther removed from said periphery with its major axis substantially parallel with the core periphery; a plurality of relatively fine wire conductors arranged within said grooves in portions thereof farther removed from said core periphery and from said bar conductors; means for conducting current to and from said bar conductors; and means for conducting current to and from the fine wire conductors.
11. In an armature for a dynamo-electric machine, the combination with a plurality of bar conductors each including branch portions having its major axis arranged at an angle to one another; of an armature core provided with grooves extending from the periphery thereof, for receiving the branch portions, said core being constructed and arranged so that said grooves cooperate with a certain branch portion of each conductor to lock the same in position; and a commutator having segments to which the branch portions are connected, said segments cooperating to maintain the branch portions in position and to prevent unlocking the said certain branch portions from the armature core.
12. A conductor for armatures of flat bar stock bent into hairpin formation and having each branch arranged to occupy portions of spaced slots in an armature core, said branches being relatively disposed so that the major axis of one branch will extend radially of the core and the major axis of the other branch will be parallel to the core periphery.
13. A conductor for armatures of flat bar stock bent into hairpin formation and having each branch arranged to occupy portions of spaced slots in an armature core, said branches being relatively disposed so that the major axis of one branch will extend radially of the core and the major axis of the other branch will be parallel to the core periphery, and so that said second mentioned branch will be located further from the core periphery than said first mentioned branch.
- In testimony whereof I affix my signature.
